D7-319

EX

OR D 19,594

UNITED STATES PATENT OFFICE.

CHARLES EDWARD HAVILAND, OF LIMOGES, FRANCE.

DESIGN FOR A DISH.

SPECIFICATION forming part of Design No. 19,594, dated January 21, 1890.

Application filed December 26, 1889. Serial No. 335,029. Term of patent 14 years.

To all whom it may concern:

- Be it known that I, CHARLES EDWARD HAVILAND, a citizen of the United States, residing at Limoges, in the Republic of France, have invented and produced a certain new and original Design for Dishes of a Table-Service, fully described and represented in the following specification and the accompanying drawings, forming a part of the same.
- 10 The leading or distinguishing features of the design are the shape of the dish and the indentations or depressions of its corners extending from the top to the bottom of the dish, and also the shape and surface ornamentation 15 of a cover for the same, substantially as shown in the accompanying illustrations, in which—
- Figures 1 and 2 show by a perspective and top view, respectively, a tea-pot and its cover in which is embodied the design of the present invention. Figs. 3 and 4 show by similar views a cream-pitcher embodying the same; and Figs. 5 and 6 by similar views show a sugar-bowl and its cover also embodying the design.
- 25 Referring to said illustrations, it will be seen that the body of each of the dishes therein

shown is of substantially rectangular form in horizontal section. Its four sides 1 swell outwardly from its top and bottom, as shown, so as to form bellied sides, and each of its four corners 2 is indented or depressed. The top edge 6 of the dish flares outward slightly, and is provided at each corner with two inward bends 3, forming curves 4—one at each corner of the dish.

The tea-pot of Figs. 1 and 2 and the sugar-bowl of Figs. 5 and 6 are each provided with a cover 5.

What I claim is—

1. The design for a dish, substantially as 40 herein shown and described.
2. The design for the cover of a dish, substantially as herein shown and described.
3. The design for a covered dish, substantially as herein shown and described.

In testimony whereof I have hereunto set my hand in the presence of two subscribing witnesses.

CHARLES EDWARD HAVILAND.

Witnesses:

ALBERT HAVILAND,
GASTON LONGEVIAL.
